MAGAZINE RACK

William S. Leath, Birmingham, Ala., assignor to EBSCO
Industries, Inc., a corporation of Delaware

Filed Nov. 24, 1965, Ser. No. 88,205

Term of patent 14 years

(Cl. D80—9)

FIG 1

FIG. 1 is a front perspective view of a magazine showing my new design;

FIG. 2 is a side elevational view of the magazine rack, the opposite side of the magazine rack being identical to the side shown;

FIG. 3 is a front elevational view of the magazine rack;

FIG. 4 is a rear elevational view of the magazine rack; and

FIG. 5 is a detail sectional view taken generally along line 5—5 of FIG. 4 showing the configuration of the upper edge of the magazine rack.

I claim:

The ornamental design for a magazine rack, as shown and described,
